ELECTRICAL ACCESSORY PLUG FOR AUTOMOBILE CIGAR LIGHTERS OR THE LIKE

Albert G. Busch, 31 Melrose Lane, Deerfield,
Lincolnshire, Ill. 60015

Filed Aug. 5, 1966, Ser. No. 3,357

Term of patent 14 years

(Cl. D26—1)

FIGURE 1 is a perspective view of my electrical accessory plug for automobile cigar lighters or the like;

FIGURE 2 is an elevational view of one end of my electrical accessory plug for automobile cigar lighters or the like;

FIGURE 7 is an elevational view of the other end of the electrical accessory plug for automobile cigar lighters or the like according to my design.

I claim:

The ornamental design for an electrical accessory plug for automobile cigar lighters or the like, substantially as shown and described.
